Primary Examiner — Lauren D McVey*Assistant Examiner* — Justin A Johnson(74) *Attorney, Agent, or Firm* — Duane Morris LLP(57) **CLAIM**

The ornamental design for a humeral implant, as shown and described.

DESCRIPTION

FIG. 1 is a perspective view of an embodiment of a humeral implant of our design;

FIG. 2 is a front view of the design of FIG. 1;

FIG. 3 is a rear view of the design of FIG. 1;

FIGS. 4 and 5 are side views of the design of FIG. 1;

FIG. 6 is a top view of the design of FIG. 1; and

FIG. 7 is a bottom view of the design of FIG. 1.

FIG. 8 is a perspective view of another embodiment of a humeral implant of our design;

FIG. 9 is a front view of the design of FIG. 8;

FIG. 10 is a rear view of the design of FIG. 8;

FIGS. 11 and 12 are side views of the design of FIG. 8;

FIG. 13 is a top view of the design of FIG. 8; and,

FIG. 14 is a bottom view of the design of FIG. 8.

All features illustrated in broken lines form no part of the claimed design.

1 Claim, 12 Drawing Sheets(56)
